UNITED STATES PATENT OFFICE.

LOUIS V. DIETER, OF WASHINGTON, DISTRICT OF COLUMBIA.

SANITARY-DRINKING-FOUNTAIN ATTACHMENT.

Application filed July 2, 1918. Serial No. 242,983.

To all whom it may concern:

Be it known that LOUIS V. DIETER, a citizen of the United States of America, residing at Washington, District of Columbia, 5 has invented new and useful Improvements in Sanitary - Drinking - Fountain Attachments, of which the following is a specification.

The invention seeks to provide, as its 10 principal object, a device of the kind mentioned in which there is provided a discharge nozzle for a stream of water, a waste pan or tank for the unused water, the waste pan being supported by the pipe conveying 15 water to the nozzle, and cover members for the nozzle, these cover members being hingedly attached to the tank and provided, since one is super-imposed above the other, with mouths in alignment and so arranged 20 that the stream ejected by the nozzle may pass through them without touching either of the cover members. The cover members provide for the complete enclosing of the 25 discharge nozzle and the upper cover is provided with means whereby it may be locked, so that access to that part of the device adjacent the nozzle may be had only by authorized persons. The upper cover member is provided with a gutter connecting with 30 its mouth and the waste water passes from this gutter into the waste tank and thence to the usual form of waste.

While illustrated in a specific embodiment, the invention is not to be restricted 35 to such embodiment. Actual practical use may suggest certain desirable changes or alterations and the right is claimed to make any which do not deviate from the scope of the annexed claims.

40 In the accompanying drawings:

Figure 1 is a perspective view of the improved device.

Figure 2 is a central longitudinal sectional view.

45 Figure 3 is a perspective view of the lower closure member.

Figure 4 is a collective perspective of the locking medium.

Referring to the drawings, there is shown 50 the extremity of a pipe 1 which is designed for connection to some suitable source of water supply. This pipe 1 at this extremity stands vertical and receives on its end the elbow 2 to which a goose neck 3 is attached, the goose neck being formed at its 55 free end to provide a discharge nozzle 4.

The pipe 1 besides acting as a supply for the goose neck and its attendant nozzle also acts as a supporting medium for the tank 5 which is shaped preferably like a rectangular parallelopiped although it may be made any other desired shape. The tank 5 is formed with a hole substantially at the center of its bottom and through this hole the pipe 1 passes, the bottom of the tank being 60 made to abut the vertical leg of the elbow 2 while a nut 6, or any other desired clamping device, abuts the bottom of the tank on the lower face and thus secures the tank in position relative to the pipe 1, the nut 6 65 threadingly engaging the said pipe 1. That clearance space may be provided for the goose neck 3, a longitudinal slot 7 is cut in the bottom of the tank 5 so that the lower portion of the goose neck may project there- 70 through, thus providing for placing the nozzle 4 as close as possible to the bottom of the tank.

An outlet member 8 is carried by the tank 5 in its bottom near that end remote from 80 the nozzle 4 and this outlet acts as a discharge for waste water.

A slight inclination is given the section 9 of the bottom of the tank, so that there may be a downward flow of water substantially 85 from the longitudinal center of the tank to the outlet 8.

Attached in opposite side walls and by that end wall adjacent to which the nozzle 4 stands, the tank carries a pintle 10 to 90 which the cover members 11 and 12 are pivotally attached. The cover member 11 comprises a plate coiled at one end to provide the spaced sleeves 13 which loosely engage the pintle. At its transverse center this 95 plate is formed with a mouth 14 and at the end remote from the sleeves 13 is bifurcated providing the spaced extensions 15 which are made arcuate in shape, so that this bifurcated end of the plate may straddle the 100 elbow 3 to permit its extensions 15 to lie on the bottom of the tank 5 at which time the mouth 14 becomes aligned with the stream projected by the nozzle 4, this stream passing through the mouth 14 without 105 touching the latter.

The cover member 12 stands above the cover member 11. This cover member is wedged-shaped in cross-section and on one bottom edge is formed with a sleeve 16 en- 110 circling the pintle 10 in the space between the sleeves 13. This construction as is evi-

dent gives the two cover members a common pivotal point. Adjacent the apex of the cover member 12 but in that wall opposite that on which the sleeve 16 is formed, there is formed a mouth 17 and this wall is shaped to provide a gutter 18 beginning at the mouth 17 and ending at the extremity of the extension 19 which is made an integral part of the wall in which the mouth 17 and gutter 18 are formed. It will be observed that the extension 19 terminates close to the bottom of the tank 5 and at its lower extremity it is made of such a shape as to tend to direct water flowing down the gutter towards the outlet 8.

The cover 12 on opposite sides but adjacent the wall in which the gutter 18 is formed is provided with the L-shaped arms 20 the free ends of which are coiled to provide eyes 21. The transverse portions 22 of these L-shaped arms rest on the upper edges of the side walls of the tank 5 and thereby limit the distance to which the cover member 12 may be lowered. Thus acting as stops for the cover member when lowered, the arms position the mouth 17 so that it aligns with the mouth 14, thus permitting the stream of water passing through the latter also passing through it without touching.

An inverted U-shaped guard 23 having its legs formed with right angle bends 25 is secured to the front face of the cover member 12 and this guard extends upwardly and 35 is braced (so that it may not be easily bent, or pressed out of shape,) by a bracing member 24 which is secured to the guard 23 in any suitable manner and likewise secured to the rear wall of the cover member 12, 40 means of securing the bracing member to the latter being also of a suitable design.

That the cover 12 may not be raised by unauthorized persons when in lowered position, a locking medium is provided in the 45 form of a rod 26 which extends transversely across the tank 5 penetrating appropriate holes formed in the side walls thereof and passing through the eyes 21 of the L-shaped arms 20. This rod 26 is headed at one end 50 and at the remaining end is formed with an eye 27 through which there may be passed a pin 28, the latter being also headed and being formed with a hole or eye 29 by means of which a lock 30 may be attached to the 55 pin. Obviously this construction provides for securing the pin in place when once attached and the pin thus being secured, the cover member 12 may not be raised and since it may not be raised, access to the cover member 11 is prevented.

In the use of the device it may or may not be provided with a cock for turning on the water when wanted. In either instance the water is projected in a continuous 65 stream from the nozzle 4 and passes upward

in a diagonal plane through the mouths 14 and 17 neither of which it touches. By placing the face against the guard 23, the mouth is brought into a convenient position so that the water may be taken thereinto, the guard 70 the while preventing the mouth from being brought into actual contact with the mouth 17, thus providing a valuable sanitary feature.

Since the cover members 11 and 12 in conjunction with the tank 5 operate to enclose the goose neck and nozzle and since the cover member 12 may be locked in such enclosing position, it is impossible for anyone but an authorized person to obtain access to 75 the goose neck and nozzle. On the other hand the cover members being hingedly mounted provision is made for the convenient cleaning of that portion of the device enclosed by the cover members. 85

The invention having been described, what is claimed as new and useful is:

1. The combination with a supply pipe, of a discharge nozzle attached thereto, a waste tank within which the discharge nozzle is 90 located, a plurality of cover members attached to the tank and serving with the latter to enclose the discharge nozzle, the cover members being provided with mouths in alignment with the stream projected by 95 the discharge nozzle, and a guard mounted on one of the covers to preclude contact of the lips of a person with the mouth of the cover.

2. The combination with a supply pipe, of 100 a discharge nozzle attached thereto, a waste tank within which the discharge nozzle is located, a pair of hingedly mounted covers in super-imposed relation, the covers being carried by the tank and serving with the 105 latter to enclose the said nozzle, the covers further being provided with mouths in alignment with the stream projected by the discharge nozzle, and a guard mounted on one of the covers to preclude contact of the 110 lips of a person with the mouth of the cover.

3. The combination with a supply pipe, of 115 a discharge nozzle attached thereto, a waste tank within which the discharge nozzle is located, a pair of hingedly mounted covers in super-imposed relation, the covers being carried by the tank and serving with the latter to enclose the said nozzle, the covers further being provided with mouths in alignment with the stream projected by the discharge nozzle, and means for locking the upper cover in its normal position of closure. 120

4. The combination with a supply pipe, of 125 a discharge nozzle attached thereto, a waste tank within which the discharge nozzle is located, a pair of hingedly mounted covers in super-imposed relation, the covers being carried by the tank and serving with the latter to enclose the said nozzle, the covers further being provided with mouths in alignment 130

ment with the stream projected by the discharge nozzle, the upper cover being formed with an extension projecting downwardly into the waste tank and having a gutter 5 formed therein in communication with the mouth, and a waste outlet in the bottom of the said tank.

5. The combination with a supply pipe, of a discharge nozzle attached thereto, a waste 10 tank within which the discharge nozzle is located, a pair of hingedly mounted covers in super-imposed relation, the covers being carried by the tank and serving with the latter to enclose the said nozzle, the covers further being provided with mouths in alignment 15 with the stream projected by the discharge nozzle, the upper cover being formed with an extension projecting downwardly into the waste tank and having a gutter 20 formed therein in communication with the mouth, a waste outlet in the bottom of the said tank, and means for locking the upper cover member in its normal position of closure.

25 6. A device of the kind described comprising a waste tank, a nozzle positioned interior thereto and provided with means for connection to a source of water supply, a pair of cover members hingedly attached to 30 the tank and designed to swing into or out of position where they enclose the said nozzle, the cover members being formed with mouths aligned with the stream projected by the nozzle, and a guard carried by one of 35 the cover members to prevent the lips of a drinker being brought into contact with the mouth of said cover member.

7. The combination with a supply pipe 40 provided with a stream discharging element, of means for enclosing said element and including a plurality of obliquely disposed cover members movable into and out of positions of closure for the said element, the 45 said cover members being in spaced relation to each other and in spaced relation to the said element and being provided with orifices aligned with the stream projected by said element.

8. A device of the kind described comprising a discharge nozzle disposed to pro-

ject a stream in a diagonal plane, an enclosure for said nozzle, and a pair of cover members hingedly attached to said enclosure and designed to swing into and out of a position of obstructing relation to said nozzle, 55 the said cover members being spaced from each other and provided with aligning orifices through which the stream projected by the nozzle may pass.

9. A device of the kind described comprising a nozzle disposed to project a stream at an angle both from the horizontal and perpendicular, an enclosure for said nozzle, and a plurality of hingedly mounted cover members carried by said enclosure and designed to swing into and out of obstructing 60 relation to said nozzle, the said cover members being provided with aligned orifices 65 through which the stream from said nozzle may pass, and locking means for the uppermost of the two cover members.

10. The combination with a stream discharging element, of an enclosure therefor including a flat shield having an opening 75 formed therein, the shield being arranged at an angle to the horizontal and in substantial perpendicularity to the stream projected by said element, the opening being out of both the vertical and horizontal planes of the outlet of said element, and means adjacent said 80 opening to guard against the descent of extraneous matter into the outlet of said element.

11. The combination with a stream discharging element, of an enclosure therefor 85 including a flat shield having an opening formed therein, the shield being arranged at an angle to the horizontal and in substantial perpendicularity to the stream projected by 90 said element, the opening being out of both the vertical and horizontal planes of the outlet of said element, and an outwardly projecting member embracing the opening and extending around the greater part of its periphery, said member being disposed at 95 the higher edge of said shield.

In testimony whereof he affixes his signature.

LOUIS V. DIETER.
